WHEEL CHOCK

Alexander Charles Ridland, Pasadena, Calif.

Application July 22, 1946, Serial No. 685,521

23 Claims. (Cl. 188—32)

1

This invention is concerned with a wheel chocking device for temporarily blocking vehicle wheels against rolling. A primary object of my invention is to produce a sturdy and effective wheel chock which can be folded into a relatively compact form when not in use. My invention further provides a mechanism which is light in weight and easy to manipulate, and which operates reliably when used on rough ground as well as on a smooth surface. At the same time my wheel chock has a structural simplicity well adapted for economical manufacture. All of these characteristics make it particularly well adapted for use with light aeroplanes, but my invention is not limited to this particular application.

Further objects and advantages of my invention and a full understanding of its nature will be appreciated from the following description of an illustrative preferred embodiment and of certain modifications thereof. This description is to be read in conjunction with the attached drawings, of which:

Fig. 1 is an elevation of an illustrative wheel chock, according to my invention, in position under a wheel;

Fig. 2 is a similar elevation of the chock in its folded position ready for stowing;

Fig. 3 is a partially cut-away plan view of the chock in its folded position;

Fig. 4 is a perspective sketch of the device in operating position;

Fig. 5 shows a fragmentary plan view, similar to Fig. 3 but including only one end portion, showing an alternative manner of constructing the chock members;

Fig. 6 is a fragmentary perspective, showing a second alternative form of the chock members;

Fig. 7 is a side elevation of a modified form of my chocking device, in position under a wheel;

Fig. 8 is a side elevation similar to Fig. 7, but showing the device in its folded position;

Fig. 9 is a partially cut-away plan view, corresponding to Fig. 8;

Fig. 10 is a transverse section of the folded device taken on line 10—10 of Fig. 9;

Fig. 11 is a perspective view of the modified wheel chock in operating position; and

Fig. 12 is an enlarged fragmentary section on line 12—12 of Fig. 9, showing preferred structure of friction treads on the chock plates.

My wheel chocking device comprises primarily an extensible frame 12 including chock carriers 16, supporting chocks 20 which are adapted to engage the periphery of the wheel 10 to be

2

chocked. The chock carriers 16 are urged toward each other by suitable tension means, maintaining the chocks in firm contact with the wheel. To facilitate stowing when not in use, chocks 20 are hinged or pivoted to chock carriers 16 and are releasably locked in their operating position (Figs. 1 and 4) by the braces 25.

In the embodiment illustrated in Figs. 1 to 4 chocks 20 are formed of single pieces of tubing, bent as indicated in the drawings, with a concave curve on their swinging ends, giving surfaces at 21 adapted to engage the rubber tire of an airplane wheel. The tube ends are flattened at 23 and drilled to form pivot bearings. Chock carriers 16 are also single pieces of tubing, formed by a single sharp right angle bend or angle at 17 into an L-shape, of which one leg 16a constitutes the chock pivot pin. The chock is restrained axially upon pivot 16a by any suitable means such as the cotter pins 18. The other leg 16b of each L-shaped chock carrier 16 enters an end of guide tube 13, which thus serves to join the two chock carriers and to guide their relative motion. This motion of chock carriers 16 and their carried chocks 20 is of two types: unrestricted rotation relative to tube 13 and to each other about the tube axis; and axial sliding motion within tube 13, limited and controlled as described below. Central guide tube 13 and chock carriers 16 thus flexibly linked to it comprise the essential structure of the extensible frame 12 mentioned above. It will be obvious, however, that the entire structure illustrated can be modified in many respects without departing from the scope of my invention.

Chock braces 25 are shown as simple rods, their upper ends 25a bent at right angles and pivoted in holes 26 in chocks 20; and their lower ends 25b similarly bent and slidably pivoted in the slots 27 cut through the walls of tubular legs 16b of chock carriers 16. Within tubes 16b the two brace ends 25b are connected to each other by spring 30 and also (preferably) by a flexible cable 31, both of which are preferably, but not necessarily, anchored midway of their lengths to the transverse pin 32 centrally placed in guide tube 13. Due to the general symmetry of the device, the two functions performed by spring 30 of urging brace end 25b and chock carrier 16 toward guide tube 13 will be performed in much the same manner whether spring 30 is anchored to tube 13 or not.

Spring 30 urges the sliding motion of brace ends 25b in slots 27 in the direction toward slot 55 ends 27a; and also, once the brace contacts the

slot end, urges the inward sliding motion of chock carriers 16 in guide tube 13. While the described structure thus permits the single spring 30 to perform two distinct functions satisfactorily, this does not prevent the use of separate spring means, if desired to urge chock carriers 16 together independently of the motion of the chock braces. Inward motion of the chock carriers is limited by contact of the end of tube 13 with brace end 25b where it enters slot 27, and is limited outwardly by cable 31, which is normally slack, but which is short enough to prevent leg 16b of chock carrier 16 from being removed completely from guide tube 13. If the outward motion of chock carriers 20 is suitably limited by other means, cable 31 can of course be omitted.

Sliding motion of brace end 25b in slot 27 in the direction toward slot end 27a raises chock 20 to its operating position (Figs. 1 and 4), while motion in the opposite direction lowers it to its folded position (Figs. 2 and 3). The end 27a of slot 27 is so located that it stops the spring urged sliding motion of brace 25 when the latter is approximately vertical, and hence when the chock is fully raised. Since the direction of brace 25 is then nearly normal to slot 27, whatever thrust the brace is required to transmit from chock 20 to chock carrier 16 can have only a small component parallel to the slot. Only moderate tension of spring 30 is therefore required to hold the brace firmly in chock supporting position against the end 27a of the slot. The slot end 27a is preferably so placed that brace 25 is slightly past vertical, as indicated in Fig. 1. Downward thrust on the brace then tends to hold it more tightly against the slot end, minimizing the danger of the brace being accidentally displaced from its chock supporting position.

The wheel engaging surface 21 of the chock is on the swinging end of the chock, and when the device is in use this surface lies generally between wheel axis 11 and chock axis 22 and close to the plane defined by these two axes. The thrust exerted by the wheel upon surface 21 is generally radial with respect to the wheel, but is slanted somewhat downward from this direction. If the wheel were free to turn on its axis, its thrust against chock surface 21 would be strictly radial. However, the wheel is restrained by its contact with the ground, and therefore actually rotates about some point at or near its ground contacting surface, tending to make the direction of thrust perpendicular to a line joining this point and chock surface 21. The actual thrust will in general be intermediate between this and the radial direction, its exact angle depending upon such factors as friction and the size, shape and structure of the wheel tire. Accordingly, my wheel chock is preferably so constructed that the chocking elements 20 in operating position project above the plane defined by wheel axis 11 and chock axis 22 at such an angle that the resultant thrust of the wheel upon chock surface 21 will be directed approximately toward chock axis 22. The thrust then has a relatively large component in the plane of the chock, and a relatively small component perpendicular to this plane. The larger component is transmitted through the chock axis to the ground, and only the smaller component is supported by brace 25.

Accordingly, chock brace 25 serves primarily to hold chock 20 in its chocking position, and does not itself sustain the main thrust of the chocked wheel 10. This is true ideally only for a wheel of the exact type for which a given chocking de-

vice is specifically designed. However, there is no need for the condition described to be satisfied accurately, and in practice a chocking device of given size can effectively accommodate a considerable range of wheel sizes. Transmission of the wheel thrust through the chock to the ground may be via carriers 16 which may be provided with ground engaging means; but is preferably through the chocks themselves, which, for this purpose, may have sharp cornered square ends.

In the folded position of Figs. 2 and 3 the chocks 20 and their braces 25 lie substantially in the same plane, and spring 30 holds brace ends 25b against the ends of tube 13. In this folded position the spring thus has no tendency to raise the chocks. To raise the chocks and prepare the device for use it is only necessary to lift the chocks toward the position of Fig. 1 and to pull them outward. This may be conveniently done by grasping the chocks at 24 and pulling up and out. During that operation brace ends 25b will remain against the ends of tube 13 as carriers 16 slide outward in tube 13 until the slot ends 27a are pulled out against brace ends 25b and the chocks are fully raised. Further outward movement of the chocks and carriers is then opposed by spring 30. Separation of chock carriers 16 is continued, distending spring 30 until cable 31 becomes taut or until the clearance between the upper extremes 30 of the two chocks 20 is sufficient to receive the wheel 10. The device is then inserted beneath wheel 10, and spring 30 is allowed to draw chock carriers 16 together until chocks 20 engage the periphery of the wheel. Spring 30 firmly maintains this engagement, and at the same time holds brace ends 25b in contact with slot ends 27a, effectively locking the braces in chock supporting position. (It may be noted that if the wheel to be chocked is too large to allow the procedure just described, the device may still be used by sliding it into position with chock carriers 16 fully separated, but with chocks 20 held flat as in Fig. 2 until after they are under the wheel.)

The chocking device can be withdrawn from under the wheel by first separating chock carriers 16 against the force of spring 30. The device is then folded by simply telescoping chock carriers 16 together within guide tube 13. When the ends of this tube contact brace ends 25b, still in the position shown in Fig. 1, these are forced to slide along slots 27, automatically folding chocks 20, and completing the preparation for stowing.

Since the device as illustrated in Figs. 1 to 4 is symmetrical with respect to the plane of base frame 12 (in its normal position), it is immaterial to which side of this plane chocks 20 swing when they are unfolded; so long as both swing to the same side. This can, of course, be arranged readily by slight manual pressure upon the chocks as chock carriers 16 are first drawn apart. The symmetry referred to is not necessary to my invention, and can be modified to suit special requirements. For example, in the particular embodiment here illustrated, the two corners 23a and 23b of the flattened chock tube ends 23 can be shaped differently to suit different types of ground. The chocks can then be swung to one side or the other of base frame 12 to bring the desired formation at 23 into use.

As has already been noted, the chock carriers with their chocks are free to rotate about the axis of guide tube 13. This rotation offers the great advantage of allowing the two chock carriers to assume different angles when used on

rough ground, thus conforming to the surface and rendering the chocking action more positive and reliable than if the entire structure were rigid.

Although the device has been described as including, and preferably does include, two oppositely disposed chocks and carriers, a single chock device which is in substance one-half of the described two-chock device may be used for some purposes. Such a single chock device would embody substantially those parts which are shown in say the left-hand half of Fig. 3, with the spring 30 in this case necessarily anchored at its right-hand end to tube 13.

The chocks 20 can of course be formed in many ways other than that illustrated in Figs. 1 to 4. For example, as illustrated in Fig. 5, they may retain their general tubular form but be pivotally mounted on chock carriers 16 by means of tube sections 40 which fit over the carrier arms 16a and act as pivot bearings. A second alternative form of chock, illustrated in Fig. 6, consists of a single sheet metal stamping 45, which may have appropriate strengthening flanges 46 and channels 47 and a flanged wheel contacting surface 48. Such a stamping can include a sleeve formation as indicated at 49 to act as a pivot bearing for carrier arm 16a. I do not intend that these particular forms of chock construction illustrated be construed as a limitation of the scope of my invention.

When my chocking device is used on a smooth surface such as a concrete floor, particularly if it is used with a wheel of relatively small diameter, the wheel may have a tendency to slide the chock over the floor. This is because the direction of thrust of the wheel against the chock makes a relatively small angle with the surface of the floor, giving a relatively large horizontal component and a relatively small vertical friction-producing component. This tendency can be reduced by the use of chock plates, such as are included in the modification of my invention illustrated in Figs. 7 to 12. Besides the use of chock plates, this modification illustrates how one chock carrier can act as frame member to support the other, eliminating the central frame member 13 of Figs. 1 to 4.

The fundamental structure and operation of this modification are the same as in that already described. However, the coaxial tubular legs of the chock carriers 56 and 57 are longer than before and are of different diameters so that one can slide within the other. The telescoping motion of one tube within the other is limited inwardly by contact of the end of each tube with the end 65b of the chock supporting brace 65 associated with the opposite carrier; and outwardly by any suitable means such as cable 68 connecting the two brace ends. The tension spring 69, attached to the two brace ends, urges them together, and also urges together the two chock carriers when the braces are in contact with the inner ends 67a of slots 67. The operation of chock supporting braces 65 to raise and lower the chock members 66 is the same as in the first described modification, with the slight distinction already mentioned that each brace end is pushed outward as the device is folded by the end of the opposite chock carrier rather than by the end of a central guide tube.

This form of my device, besides eliminating the central guide tube, allows somewhat greater longitudinal flexibility of the device, thus allowing it to embrace a larger wheel or fold to a more compact size or both. It will be evident that with

this form there is no need of centrally anchoring spring 69 and cable 68.

The chock plates 75 are shown in Figs. 7 to 12 as steel pressings. These are essentially flat but have strengthening flanges 76 along their sides and friction ridges 77 on their upper faces. These ridges can be formed, as shown in Fig. 12, like the well-known louvre openings such as are frequently used to provide ventilation. Chock plates 75 are secured to the remainder of the structure only at their outer ends which are pivoted to the upper ends of chocks 66 for rotation about axes parallel to those of the chock pivots 56a and 57a. Preferably the pivot axes of the chock plates are formed simply by extensions of the upper ends 65a of chock supporting braces 65, as shown most clearly in Fig. 9.

In operating position under the wheel chock plates 75 are supported at their upper ends by these pivots, and their lower ends rest directly on the ground, as shown in Fig. 7. They are so proportioned that as the wheel starts to roll the tire presses downward on the lower part of the chock plate. The direction of this thrust being nearly vertical, it creates a strong frictional resistance to slipping at its surface of contact with the ground. This prevents the entire device from sliding. The main thrust of the wheel is transmitted from the upper portion of the chock plate through pivot 65a to the chock itself and, as before, longitudinally through the chock to the ground.

When the device in its present form is folded the projecting ears 81 welded to the sides of chock plates 75 contact the upper surface of the chock carriers and force the plates to rotate about pivots 65a into the plane of chocks 66, as shown in Fig. 8. The plates are prevented from turning beyond this position by contact with stops 78 welded to the cross members 66a of the chocks. Thus when folded, the position of the plates is restricted by stops 78 on the one hand and ears 81 on the other, insuring a compact form of the entire device. As the chock carriers 56 and 57 are telescoped together one chock plate partially nests inside the other. To facilitate this nesting one plate is made slightly wider than the other, as can be seen clearly in Fig. 9, and one of the ears 81 is preferably attached to its plate in a slightly higher position than the other, as is shown in Fig. 8. Ears 81 are preferably so located on the chock plates that in operating position they are well clear of the chock carriers, as in Fig. 7, so that the swinging ends of the plates are supported only by contact with the ground or floor.

Various other changes and modifications may be made from the illustrative designs which have been described without departing from my invention, the scope of which is defined in the following claims. In these claims I use the term "telescopic," with relation to frame member 13 and carrier 16, or with relation to two carrier members such as 56 and 57, to denote capability of relative extensive and contractive movement, whether or not one member slides with relation to the other, or, if it slides, whether or not the two members are relatively sliding tubes. For instance, it is sufficient to the described functioning of my device that the chock carriers be movable in contractive and extensive relation to the member called the frame or with relation to each other. And if that movement is one of sliding, the sliding association of the frame and carrier 75 may be of any suitable formation, although a

tubular formation is preferable for simplicity and for the flexibility which has been noted. When one chock carrier is related directly to the other without any intervening frame member, each carrier is to be construed as forming a frame for the other. And I may also note that, if a tubular or similar sliding formation is used, it is immaterial whether the frame tube or the carrier tube is the external one.

I claim:

1. In a device for chocking a wheel, two chock carriers telescopically related for longitudinal relative motion between relatively contracted and extended positions and also for relative swivelling movement about a longitudinal axis, a chock swingably mounted on each carrier to swing about a transverse chock axis between a folded position essentially in a longitudinal plane and an operating position projecting above that plane, and chock holding members each associated with a chock and the corresponding carrier and adapted to hold the chock in its operating position.

2. A device as defined in claim 1, and also including a frame member extending longitudinally between the two chock carriers and telescopically and swivelly related to each carrier.

3. In a device for chocking a wheel, two chock carriers telescopically related for longitudinal relative motion between relatively contracted and extended positions, a chock swingably mounted on each carrier to swing about a transverse chock axis between a folded position essentially in a longitudinal plane and an operating position in a plane projecting upward from the longitudinal plane, and means acting between each chock and its corresponding carrier to support the chock in its operating position.

4. In a device for chocking a wheel, two chock carriers telescopically related for longitudinal relative motion between relatively contracted and extended positions, a chock mounted on each carrier for swinging movement about a transverse axis thereon between a folded position essentially in a longitudinal plane and an operating position in a plane projecting upward from the longitudinal plane and inward from the said axis, and means for releasably supporting the chocks in their operating positions.

5. In a device for chocking a wheel, two chock carriers telescopically related for longitudinal relative motion between relatively contracted and extended positions, chocks movably mounted on the carriers for motion relative thereto into and out of operating positions, means for releasably confining the chocks in their operating positions, said means being movable into and out of chock confining positions, and means associated with the chock confining means and adapted to move the confining means to chock confining position by virtue of motion of the chock carriers toward their relatively extended positions.

6. In a device for chocking a wheel, two chock carriers telescopically related for longitudinal relative motion between relatively contracted and extended positions, chocks movably mounted on the carriers for motion relative thereto into and out of operating positions, means for releasably confining the chocks in their operating positions, said means being movable into and out of chock confining positions, and means associated with the chock confining means and with the carriers and adapted to move the carriers out of their chock confining positions by virtue of motion of

the carriers toward their relatively contracted positions.

7. In a device for chocking a wheel, two chock carriers telescopically related for longitudinal relative motion between relatively contracted and extended positions, chocks movably mounted on the carriers for motion relative thereto into and out of operating positions, means for releasably confining the chocks in their operating positions, said means being movable into and out of chock confining positions, spring means tending to move the chock confining means into their chock confining positions, and means for moving the chock confining means out of their chock confining positions by virtue of motion of the chock carriers toward their relatively contracted positions.

8. In a device for chocking a wheel, two chock carriers telescopically related for longitudinal relative motion between relatively contracted and extended positions, chocks movably mounted on the carriers for motion relative thereto into and out of operating positions, means for releasably confining the chocks in their operating positions, said means being movable into and out of chock confining positions, and unitary spring means tending to move said chock confining means into their chock confining positions and to move the chock carriers toward their relatively contracted positions.

9. In a device for chocking a wheel, a frame member, a chock carrier telescopically related to the frame member for longitudinal relative motion between relatively contracted and extended positions, a chock swingably mounted on the carrier to swing about a transverse chock axis between a folded position essentially in a longitudinal plane and an operating position projecting above that plane, releasable means for holding the chock in its operating position with relation to the carrier, said means movable between chock-holding and chock-releasing positions, and means associated with the frame member and the chock holding means and tending to move the holding means to its chock-holding position by virtue of movement of the carrier toward its extended positions.

10. In a device for chocking a wheel, a frame member, a chock carrier telescopically related to the frame member for longitudinal relative motion between relatively contracted and extended positions, a chock swingably mounted on the carrier to swing about a transverse chock axis between a folded position essentially in a longitudinal plane and an operating position projecting above that plane, releasable means for holding the chock in its operating position with relation to the carrier, said means movable between chock-holding and chock-releasing positions, and means associated with the frame member and the chock holding means and tending to move the holding means to its chock-releasing position by virtue of movement of the carrier toward its contracted position.

11. The device defined in claim 9 and in which the last mentioned means comprises a tie member connected between the holding means and the frame member.

12. The device defined in claim 9 and in which the last mentioned means comprises an extensible spring tie member connected between the holding means and the frame member.

13. The device defined in claim 10, and also including means associated with the frame member and the chock holding means and tending to move the holding means to its chock holding posi-

tion by virtue of movement of the carrier toward its extended position.

14. In a device for chocking a wheel, a frame member, a chock carrier capable of longitudinal motion relative to the frame member, a chock mounted on the chock carrier and rotatable about a transverse axis between a folded position essentially in a plane through said axis and parallel to said longitudinal motion and an operating position projecting out of that plane, a brace pivoted on the chock and slidably pivoted on the chock carrier for longitudinal sliding motion, a stop limiting the said sliding motion at a point at which the brace is at an angle to the direction of said sliding motion and supports the chock in its operating position, and spring means tending to move the brace toward the stop.

15. In a device for chocking a wheel, a frame member, a chock carrier capable of longitudinal motion relative to the frame member between a relatively extended position and a relatively telescoped position, a chock mounted on the chock carrier and rotatable about a transverse axis between a folded position essentially in a plane through said axis and parallel to said longitudinal motion and an operating position projecting out of said plane, a brace pivoted on the chock and slidably pivoted on the chock carrier for longitudinal sliding motion, a stop limiting the said sliding motion in a direction toward the frame member at a point at which the brace is at an angle to the direction of said sliding motion and supports the chock in its operating position, spring means tending to cause motion of the brace toward the stop, and a surface on the frame member adapted to contact the brace and to cause sliding motion of the brace away from the stop when the chock carrier approaches its said telescoped position on the frame member.

16. A chocking device as defined in claim 15, and in which the spring means comprises a spring attached at one end to the sliding end of the brace and effectively attached at the other end to the frame member, so that the spring tends to move the carrier toward its telescoped position when said end of the brace is against the stop.

17. A chocking device as defined in claim 15, and in which the frame member is in the form of a tube, and the chock carrier in the form of a telescopically related tube, the spring means being a tension spring lying within the two tubes and attached at one end to the sliding end of the brace and effectively attached at the other end to the frame tube, and the end of the frame tube constituting the surface on the frame adapted to contact the brace.

18. In a device for chocking a wheel, a frame tube, a chock carrier tube adapted for longitudinal telescopic movement with relation to an end of the frame tube, a transverse axis member carried by the carrier tube, a chock swingable about said axis member between a position substantially in the plane of the tubes and the axis member and a position projecting from that plane, the carrier tube having a slot through its wall extending from a slot closed end outwardly away from the end of the frame tube, a chock brace pivotally connected at one end to the chock and having its other end extending through said slot for pivotal and sliding movement therein, and a spring located within the tubes and effectively connected to the sliding end of the brace tending to move that end of the brace toward the closed end of the slot.

19. In a device for chocking a wheel, a frame

tube, a chock carrier tube adapted for longitudinal telescopic movement with relation to an end of the frame tube, a transverse axis member carried by the carrier tube, a chock swingable about said axis member between a position substantially in the plane of the tubes and the axis member and a position projecting from that plane, the carrier tube having a slot through its wall extending from a slot closed end outwardly away from the end of the frame tube, a chock brace pivotally connected at one end to the chock and having its other end extending through said slot for pivotal and sliding movement therein, and a spring located within the tubes and effectively connected to the frame tube and the sliding end of the brace tending to move that end of the brace toward the closed end of the slot, and tending to move the carrier tube toward the frame tube when the brace contacts the slot end.

20. In a device for chocking a wheel, a frame member having two longitudinally opposite ends, two chock carriers telescopically related respectively to the two frame ends, and adapted to move longitudinally inwardly and outwardly with relation thereto between contracted and extended positions, a chock mounted on each carrier for swinging movement about a transverse axis thereon between a position essentially in a longitudinal plane and a position projecting from that plane, a brace pivoted to each chock and pivoted slidably to the respective carrier to have longitudinal sliding movement with relation to the carrier, each carrier having a stop which limits the inward sliding movement of the associated brace to a position in which the brace is at an angle to its directions of sliding movement on the carrier, and spring means acting effectively between the sliding ends of the two braces tending to move them toward each other.

21. In a device for chocking a wheel, a ground engaging frame, two chocks mounted on the frame in longitudinally spaced relation and swingable about transverse chock axes between folded positions essentially in a longitudinal plane and operating positions projecting above that plane, the line of intersection of the planes of the two chocks in said operating positions lying above the said longitudinal plane, ground engaging chock plates mounted on the swinging ends of the chocks for pivotal movement about axes essentially parallel to the said chock axes, said chock plates having ground engaging surfaces at their swinging ends and being swingable between folded positions essentially in the planes of the chocks and operating positions at such an angle that the line of intersection of the planes of the chock plates lies below the said longitudinal plane, and means for releasably supporting the chocks in their operating positions.

22. In a device for chocking a wheel, a generally flat frame, a generally flat chock pivotally mounted on the frame for swinging motion about a pivot axis which lies substantially in the plane of the frame and in the plane of the chock, the chock carrying a wheel engaging surface generally transverse of the chock plane on one side of the said axis, and carrying two alternative ground engaging formations on the other side of the said axis and oppositely disposed with respect to the plane of the chock, said chock being swingable about the said axis between two operating positions substantially symmetrically disposed on opposite sides of the frame, and releasable means for confining the chock selectively in either of the said operating positions.

11

23. In a device for chocking a wheel, a ground engaging frame, two chocks mounted on the frame in longitudinally spaced relation and swingable about transverse chock axes between folded positions essentially in a longitudinal plane and operating positions projecting above that plane, the line of intersection of the planes of the two chocks in said operating positions lying above the said longitudinal plane, ground engaging chock plates mounted on the swinging ends of the chocks for pivotal movement about axes essentially parallel to the said chock axes, said chock plates having ground engaging surfaces at their swinging ends and being swingable between folded positions essentially in the planes of the chocks and operating positions at such an angle that the line of intersection of the planes

of the chock plates lies below the said longitudinal plane, the swinging ends of the chock plates in their operating positions being supported only by their ground engagement, and means for releasably supporting the chocks in their operating positions.
